UNITED STATES PATENT OFFICE.

JAMES C. WOODSON, OF EAST PITTSBURGH, PENNSYLVANIA, ASSIGNOR TO WESTINGHOUSE ELECTRIC & MANUFACTURING COMPANY, A CORPORATION OF PENNSYLVANIA.

ELECTRIC HEATING UNIT.

Application filed July 6, 1923. Serial No. 649,803.

To all whom it may concern:

Be it known that I, JAMES C. Woodson, a citizen of the United States, and a resident of East Pittsburgh, in the county of Allegheny and State of Pennsylvania, have invented a new and useful Improvement in Electric Heating Units, of which the following is a specification.

My invention relates to electric heating devices and particularly to electric heating units.

The object of my invention is to provide a relatively simple and compact removable electric heating unit, that shall be capable of being easily and quickly applied to any device to be heated.

In practicing my invention, I provide a plurality of elongated, relatively narrow, refractory members of electric-insulating material, each having a plurality of undercut grooves extending laterally thereof in one face.

A plurality of these supporting members are located in co-extensive and closely adjacent, parallel relation, and a terminal-member supporting-bar is provided at each end of the plurality of refractory bars. Bars of non-oxidizing metal are provided at each side of the assembled group of refractory bars to hold them in their proper operative positions relatively to each other. The ends of the metal bars overhang the group of refractory bars and are perforated to permit of placing therethrough a suitable supporting bolt. A helically wound resistor member is located in the undercut grooves and has its ends connected to suitable terminal members on the end bars of refractory material.

40 In the single sheet of drawings,

Figure 1 is a top plan view of an electric heating unit embodying my invention,

Fig. 2 is a view, in end elevation thereof, and

45 Fig. 3 is a view, in side elevation, of one of the refractory resistor-supporting bars.

A quickly removable heating unit 11 comprises a plurality of refractory bars 12 of a suitable electric-insulating material that are relatively narrow and elongated, and are severally provided with a plurality of spaced and undercut grooves 13 in one of the faces thereof. The end portions of each of the bars 12 are of less thickness than the

main portion thereof, for a purpose to be 55 hereinafter described in detail.

End bars 14 of substantially the same area in lateral section and of substantially the same length are provided at each end of the assembled group of bars 12 and are 60 severally provided with an intermediate depressed portion 15 and end depressed portions 16 and 17. Ridges 18, of substantially H-form, are located between the depressed portions 15 and 16, and 15 and 17, respectively.

A helically wound resistor member 19 extends through the spaced grooves 13, being held in the lower portion thereof by the overhanging portions or teeth 21, as illustrated more particularly in Fig. 3 of the drawing. It is, of course, understood that the grooves 13 in the respective bars are in alinement when the bars 12 are located in parallel and co-extensive positions, substantially as illustrated in Fig. 1 of the drawing.

75 Terminal members are mounted on the respective end bars 14 and may comprise bolts 22 and a plurality of nuts 23 having screw-threaded engagement therewith, suitable 80 openings 24 being provided in the end bars 14 to permit of mounting the bolts therein. The resistor member 19 may extend from one of the terminal members, say at the left-hand end of the assembled unit, through one 85 outer groove to the right-hand end of the unit, then back in the next adjacent groove to the left hand end, then back and forth until its other end is secured to the intermediate terminal member located in the bar 90 14 at the right hand end of the assembled unit, as illustrated in Fig. 1. In this way, it is possible to employ two spaced heating elements and to employ therewith any suitable or desired method of control to permit 95 of selectively varying the energization of the heating elements.

It may be noted that the upstanding walls or ridges 18 are of such shape as to assist in effectively insulating the end portions of 100 the heating element from each other as is more particularly shown in the left hand end of Fig. 1.

Means for holding the bars 12 and 14 in proper operative positions relatively to each 105 other comprise an angle bar member 25 that is made of a suitable nonoxidizable material such as a nickel chromium alloy and of a

flat bar 26. The angle bar 25 has one of its flanges fitting in a shoulder portion 27 of the bars 12 and 14 and the bar 26 is located at the other surface of the bars substantially as illustrated in Fig. 2 of the drawing. A plurality of flat head machine bolts 30 and co-operating nuts 28 are provided for each end of the bars 12 and 14 whereby a substantially unitary and easily removable heating unit structure is obtained.

The angle bar members 25 may extend a short distance beyond the assembled group of bars and have elongated openings 29 at each end to permit of securing the assembled heating unit against a suitable supporting surface or against a surface that is to be heated thereby.

The metal side bars 25 and 26 may be removed when it is desired to apply the heating unit against a curved surface that will support the same. The helically wound resistor member serves to hold the refractory bars in substantially their operative positions while permitting them to adjust themselves to the contour of the surface against which they are located.

The device embodying my invention thus provides a relatively simple, easily assembled and disassembled heating unit structure comprising relatively few parts that shall permit of radiating a relatively large amount of the heat directly against any surface or body to be heated, and that shall embody means to permit of securing it by relatively simple means against a supporting surface or against the surface to be heated.

Various modifications and changes may be made without departing from the spirit and scope of the invention, and I desire, therefore, that only such limitations shall be placed thereon as are imposed by the prior art or are set forth in the appended claims.

I claim as my invention:

1. An electric heating unit comprising a plurality of relatively narrow, elongated, refractory bars located in adjacent relation and

each having undercut and laterally-extending grooves in one face thereof, an extended heating element located in the undercut grooves and means extending along the ends of said bars and secured thereto for holding all of said bars in proper operative positions relatively to each other.

2. An electric heating unit comprising a plurality of elongated and relatively narrow bars of refractory electric insulating material located in closely adjacent relation, each bar having a plurality of spaced, undercut, and laterally-extending grooves in one face thereof, the grooves in the bars being in lateral alignment with each other, a helically-wound resistor member located in said undercut grooves, a refractory terminal-supporting bar at each end of said plurality of bars, terminal members for said resistor member on said end bars, and refractory and substantially non-oxidizable metal members at the ends of said bars for holding them in proper operative positions relatively to each other.

3. An electric heating unit comprising a plurality of laterally-grooved, narrow, elongated, refractory bars located in coextensive and closely adjacent relation, means secured to the ends of said bars for holding them in such positions, and an electric heating element extending back and forth in said grooves.

4. An electric heating unit comprising a plurality of laterally-grooved, narrow, elongated, refractory bars located in co-extensive and closely adjacent relation, an electric heating element located in said grooves, and means secured to the ends of said refractory bars for holding them in their proper operative positions relatively to each other and for permitting the mounting of the heating unit in any desired operative position.

In testimony whereof, I have hereunto subscribed my name this 2nd day of July, 1923.

JAMES C. WOODSON.
